Application July 10, 1933, Serial No. 679,606

9 Claims. (Cl. 18—8)

This invention relates to thread-processing apparatus provided with mechanism for automatically transferring the thread or the like.

In the manufacture of artificial silk thread, particularly by the viscose process, it is possible to subject the thread to the necessary operations by running the thread over a plurality of reels, acting as thread store devices, on each of which is performed some one operation, such as washing, desulphurizing, souring, drying, etc. As described in British Patent No. 413,413, the thread passes over a given reel in a form which may be considered helical, although it is not truly so, traveling from one end of the reel to the other and being, in effect, stored thereon for a sufficient length of time to permit the desired operation to take place. The thread then descends to the next lower reel, placed thereunder, where it travels across such second reel in the reverse direction while winding in the same direction, and so on for as many reels as may be employed. In a commercial machine, each row of reels handles one thread through all stages between the spin bath and the packaging device. Unit reels are preferably used, i. e., reels which carry only one thread, but it is also possible to employ reels which carry a number of threads.

In machines utilizing a multiplicity of such reels, it is obviously necessary as a part of the operation which puts the machine as a whole into operation to accomplish transfer of the thread from reel to reel and from the final reel to the take-up device. In co-pending application Serial No. 679,640, filed July 10, 1933, there has been described a method and means for positively and with certainty producing a free leading end when the thread reaches the discharge end of a reel, as by breaking, tearing or otherwise severing the thread at a point back of the actual leading end thereof. The newly established leading end is freed from the reel in such manner that it can unwind therefrom and carry over to the next succeeding reel or the takeup device. Such method is, however, a manual one and the mechanism described requires the attention of an operator in order to effect each transfer. Consequently, where a large number of threads are being run in a given plant, and these may number many thousands even in a plant of moderate size, it will be seen that the labor, time and expense involved in transferring each of these threads over a number of reels, which may be as many as nine, more or less, involves considerable expense in putting each machine into operation, as

The present invention contemplates a method for producing a free leading end on each thread as it reaches the discharge end of each reel in turn; automatically removing this free end from the reel surface, even though the latter is wet; and causing such free end to contact with and wind onto the next reel or to collect in any desired form. Among other things, it is an object of the invention to provide means for automatically forming a new leading end and freeing such end from the reel. Another object of the invention is to provide means for positively and automatically transferring the thread in such manner that the running of the thread is not interrupted. Still another object of the invention is to provide a method of automatically forming a new leading end and automatically removing such leading end from the reel. Other objects of the invention will in part be obvious and will in part appear hereinafter.

While the invention is adapted for use in connection with any process of making artificial silk thread, such as the cuprammonium, cellulose nitrate, cellulose acetate and viscose processes, it is especially valuable and will be described in connection with the viscose process although no limitation is thereby implied. In fact, the method and apparatus of the invention may be used wherever it is necessary to transfer a thread or thread-like article from one rotating surface to another, especially if the thread or thread-like article to be transferred is wet and tends to cling to the surface from which it is to be removed. In the drawings, which illustrate one manner of carrying out the invention, Fig. 1 is a front elevation of a portion of a spinning machine with the thread-forming mechanism in place; Fig. 2 is a section taken along the line 2—2 of Fig. 1; Fig. 3 is a vertical section, somewhat enlarged, through two of the thread-removing mechanisms in operative position; and Fig. 4 is a section taken along the line 4—4, Fig. 3.

In the viscose process, a thread is formed from the viscose in a setting bath and this thread, made up of a number of fine filaments, is collected and subjected to various treatments, as mentioned above, to purify it and leave a thread of regenerated cellulose which will not deteriorate in use due to the action of chemicals which might otherwise be left in the fiber. Each of the stages or steps of the manufacturing process after the thread has been formed in the spin bath may advantageously be conducted by running the thread over a reel and spraying or dipping the bath of the chemical or

other liquid which it is desired to apply to the thread at that point in the process. The next subsequent step may then be performed on the following reel and so on to the end. The reels 5 are preferably positioned one below the other, either vertically or offset, but it is also possible to run the thread horizontally from one reel to another.

In a machine of this kind involving a plurality 10 of spinning reels, the thread is, in effect, temporarily stored on the reels due to the fact that it remains on such reel for such length of time as is necessary to complete its travel across the reel, for the purpose of giving each treating operation 15 an opportunity to be completed with respect to each thread. To place the machine in operation, the reels are started rotating and the thread being formed at the spinneret in the spin bath is taken up by hand and led from the spinneret 20 through any necessary guides and is applied to the receiving end of the first reel. Succeeding helical turns of thread are now produced and progress toward the discharge end of the reel where it is obviously necessary that the end of 25 the thread be taken off, carried over, and applied to the receiving end of the second reel. The thread end must thus be transferred from reel to reel until it has been completely treated and formed into a finished thread and passed to a 30 packaging device or the like.

According to the present invention, the carry-over from the discharge end of one reel to the receiving end of the next reel is accomplished in the manner hereinafter described:—

35 As the leading turns of thread approach and reach the discharge end of the first reel, regardless of whether the actual leading end is washed under or bound beneath following turns, there is applied to the reel and to the threads thereon, at 40 a point near the discharge end of the reel, any suitable rotatable device which has the effect of cutting, breaking, shearing or otherwise severing the thread back of the actual leading end to create a new free leading end not bound beneath 45 following turns and which also has the effect of removing this freshly formed leading end from the reel surface, whether or not the latter is wet. The act of removing the thread from a given reel involves two steps; to wit, the formation of 50 a new free end and the removal of this free end from the wet surface of the reel, as by blowing a stream of air or other fluid thereagainst, the removal being aided by either gravity or centrifugal force or both. Upon contact with the next 55 reel, the thread commences to wind on such reel without further assistance. The described method is more particularly intended for use in a spinning machine wherein the reels are positioned one below the other; but it can also be 60 employed in connection with machines in which the thread is carried horizontally from one reel to another or in any other feasible direction. In any case, it is necessary only to touch the thread end to the second reel, whereupon surface tension causes it to cling thereto and begin to wind 65 thereon.

Various means may be employed to perform the above described method, provided that such means are rotatable at a fairly high rate of 70 speed in order to create windage which will assist in removing the thread end from the reel. Such means may consist of a disk-like member having radially disposed elements capable of exerting the cutting, abrading, tearing or other severing action on the thread when applied against the reel, 75

the radial elements being preferably of a resilient material or resiliently mounted in the disk-like member so as to reduce wear on the reel to which the device is applied. It is also desirable to mount the disk, which is equipped with driving 5 means independent of the drive for the reel, in a resilient manner so that contact with the reel is reduced to a minimum or completely avoided when the transfer mechanism is not in use. Any such device may be used provided only that it is 10 capable of rotation at a sufficiently high speed to produce adequate windage to remove the thread end formed by severance from the wet reel. By way of example, the method may be performed by means of a simple rotatable wire 15 brush suitably mounted for rotation and held with its bristles contacting with the reel. One or more turns of thread will be severed by the bristles when the thread has traveled to the end of the reel where the brush is mounted and the 20 windage from the rotating brush will blow the severed end away from the reel. Such means may be equipped, for example, with passages for the purpose of inducing a greater flow of air under the impelling action of the radial elements referred to or such adjuncts may be dispensed with, as desired.

Referring to Figs. 1 and 2, the reels 1, 2 and 3 are mounted in a frame, of which one of the uprights 4 is shown. Each horizontal row of reels is 30 surrounded by a housing 5 which confines the liquid showered on to the reel except in the case of the upper row where the housing is left open at the top to permit the thread to be brought manually from the spin bath to the reel. A 35 guard 6 is provided to deflect spray from the front of the apparatus. The treating medium may be any one of the various solutions or washing media applied to the thread during the process of treatment and is distributed over the reel 40 and thread by a perforated pipe 7 or by a trough or any other suitable device. The liquid is collected in a trough 8 at the bottom of the housing, being returned to the distributing device by means of a pump diagrammatically indicated at 9. The 45 distributing system may assume various forms and it is intended to indicate the same, for the purposes of the present invention, only in a more or less general way. Assuming the reel 1 to be the first reel of a series, the thread 11 is brought 50 from the spin bath (not shown) through the open top of the uppermost of the several casings 5 and is applied manually to the starting end of such reel.

All of the reels in the machine having previously 55 been started rotating, the thread follows a helical path around reel 1 due to the construction of such reel. The reel preferably consists of two cages made up of bars 12 and bars 13 alternating therewith, each set of bars going to make 60 up one of the cages. The cages are both offset and canted with respect to each other and rotate eccentrically about the centers 14 and 15. This results in relative movement of the bars 12 and 13, so that the thread is alternately carried by 65 one set of bars and then by the other set of bars. At the same time, due to the canted relation of the bars, the thread is advanced along the reel as it is alternately picked up and dropped by each set of bars. This results in the thread being 70 wound on the reel in a single layer and spread out so as to be effectually treated by the liquid applied to the reel.

According to the present invention transfer of the thread from reel to reel is accomplished by 75

permanently positioning a rotatable thread-severing means 16 adjacent the discharge end of the reel 1 and of all reels in the installation. The latter device includes a disk-like member 17 having radially disposed blades or irregularities that constitute thread-severing elements. The disk is rotated in the same direction as the reel with which it cooperates, thus causing the contacting surfaces of the two to move in opposite directions. A thread traveling along the reel in a generally helical path is immediately severed by the rotating disk so as to provide a free thread end regardless of any under-wind or under-wash of the thread. The high speed of rotation of the disk also sets up windage which blows this free end away from the reel.

The thread-severing device 16 is mounted in a combination housing and bracket 18 which is inserted into an opening in the housing 5, being resiliently mounted therein by means of a gasket 19 made of rubber or other suitable material. A clip 20 on the housing 5 cooperates in retaining the bracket in the opening in the housing. The disk 17 is mounted on a spindle 21 and is driven by means of a belt 22 running over a pulley 23. There will be one of these pulleys for each transfer mechanism, all mounted on a jack shaft 24, there being a jack shaft for each horizontal row of mechanisms. Each jack shaft is driven through a spiral gear 25 meshing with another gear 26 at right angles thereto and keyed to a shaft 27 driven by a motor (not shown). This arrangement of the thread-removing devices is independent of the drive for the reels, which have their own pulleys 28 and 29 driven by belts 31 which are operated by another motor. If desired, one motor may be used to drive both the reels and the transfer mechanisms with a clutch for connecting and disconnecting the transfer mechanisms.

The bracket 18, which, together with the transfer mechanism, is removable as a unit from the housing, holds the disk 17 resiliently against the surface of the reel 1 with just enough contact so that the thread is cut or otherwise severed when it reaches the disk. Adjustment of the disk with relation to the surface of the reel may be had by means of the screw bolt 32 carrying a lug 33 bearing against the lower part of the bracket 18. The screw bolt lies below the housing 5, which is shown as recessed to receive it, and is equipped with nuts 35 bearing against bracket 36, whereby pressure may be exerted against the lower part of the bracket 18 to swing the same about clip 20 as a pivot, forcing the bracket against the lower part of the gasket 19 and thus bringing the disk 17 closer to the reel. Loosening the nuts will effect the opposite result.

In order to minimize wear of the reel surface and also of the transfer device when the latter is thus brought into contact with the reel, the radial elements, which may be separate parts mounted on the spindle 21 or which may be irregularities in the surface of the disk itself, are either made of a material soft enough not to abrade or cut the outer surfaces of the reel bars while yet hard enough to sever the thread thereon or are resiliently mounted on the spindle 21 so as to yield somewhat as they contact with the reel. Such construction does not interfere with the removal of the thread but does minimize wear of the reel.

As mentioned above, the disks 17, of whatever construction, are rotated rapidly in the same direction as the reels, the surfaces of contact mov-

ing in opposite directions. Their action is such that the helically traveling thread is immediately severed when it reaches the zone of contact of the disk with the reel. The severed end thus formed is immediately removed from the surface of the reel, whether or not such surface is wet, by the windage set up due to the high speed of rotation of the disk 17. This causes the severed end, which is provided in free condition regardless of underwashing or underwinding of the thread to leave the surface of the reel as indicated at 37. The free end then billows out as indicated by the intermediate position 38 until it contacts with the surface of the reel 2. It is quickly drawn straight as it commences winding on the latter reel assuming the position 39. This completes the transfer of the thread from the first reel to the second. Openings 40 and 41 are provided in the casing of the upper and lower reels, respectively, to permit the thread to run from one reel to another.

Once the thread has been started winding on a subsequent reel, the transfer wheel cannot again cut it since the thread will not travel beyond the point at which it runs off to the subsequent reel; on the other hand, if the thread should be broken between two reels, it would again be free to travel across the first of such reels until it reaches the transfer mechanism and is again severed and transferred.

The thread now travels helically across the second reel, but in the opposite direction to that followed on the first reel, until it reaches the zone of contact of another disk 17, constituting the thread-removing element of the transfer device provided for the latter reel. The action here is the same as in the preceding case and the thread is quickly and automatically removed and contacted with reel 3. This action continues in sequence until the thread is winding helically over each reel in turn and following a continuous path from the spin bath to the packaging device or other collecting location. No further attention has been required from the operator after he has once started the motor which drives the transfer mechanisms. When the thread is observed to be running onto the packaging device or to be otherwise collecting, the operator may shut off the motor until such time as it is again necessary to set the machine in operation. Since one motor may drive a large number of jack shafts, each shaft carrying the thread-removing mechanisms for each of the nine stages, more or less, involved in treating one thread, it is apparent that very little attention is required in order to put a given machine in operation. Even this slight attention may be dispensed with if the transfer mechanisms are left running at all times, as may be done where wear and power consumption are not great.

Referring now to Figs. 3 and 4 of the drawings, there is illustrated a preferred mechanism for effecting removal of a thread from a reel, although it will be understood that many other mechanisms may also be used for carrying out the method of the invention. In general outline, the mechanism includes a rotatable shaft and driving means therefor, the shaft carrying radially disposed blades which constitute the thread-severing elements of the device. These blades are intended to be rotated in the same direction as that of the spinning reel adjacent to which they are mounted, thus causing the blades to move in the opposite direction to the reel surface at the point of contact. These blades project

between two disk-like plates, hereinafter called shrouds, one of which rotates with the shaft and the other of which is stationary, the purpose of the shrouds being to exclude thread ends from contact with moving parts of the mechanism and prevent consequent clogging of the mechanism by a collection of these thread ends. The shrouds also aid in directing a stream of air, set up by the rotation of the blades, against the thread end 10 which has been severed by these blades. The radially disposed blades are mounted on a ring of flexible material, such as rubber, secured around the shaft by appropriate annular members, such resilient mounting being for the purpose of causing the heads of the blades to contact with the reel with a yielding action which severs the thread but does not cause severe wear between the two oppositely rotating surfaces.

The mechanism consists of the spindle 42 carrying a pulley 43 rigidly mounted against the button head 44, the belt 22 running over this pulley and one of the pulleys 23. At its other end, the spindle carries a rotating shroud 45 held on the shaft by means of a nut 46 engaging with the threaded end of the spindle. A stationary shroud 47 is positioned back of the rotating shroud and has an annular rearwardly extending portion 48 which surrounds the spindle for a portion of its length and has a threaded outer surface engaging 30 with a threaded shoulder 49 on the bracket 18. The inner surface of the portion 48 surrounds and secures babbitt bearings 51 and felt oil retainers 52, in which the spindle 42 rotates.

The rotating shroud 45 and stationary shroud 47 are curved toward each other at the periphery of the disk to provide a narrow circumferential slot through which the radially disposed blades 63 project. The manner in which these blades are mounted is an important feature of the construction of the device. A ring 53 of some resilient material, such as soft rubber, is positioned around the spindle 42, such ring being held within the space provided between an inner retaining cup 45 and an outer retaining cup 55. Both of these cups have flanges extending for a short distance radially along the blades to constitute a support for the latter at right angles to the axis of rotation for a portion of their length. The blades 63 are bent or formed at their inner ends to provide a right angle foot 56 adapted to rest on the ring 53, the blades being of such number and the feet of such width as to completely fill the inner circumference of the outer retaining cup 55 with approximately .002" to .003" clearance. The inner retaining cup 54 passes through the hole in the ring 53 and supports the ring against the blade feet.

The effect of this resilient mounting of the blades is to permit a slight radial movement thereof toward the axis of the spindle and also a slight angular movement thereof along the periphery of the wheel. Upon encountering the surface of the reel, the blades tend to be pushed closer to the center of the wheel, due to the combined radial and angular motion made possible by the resilient mounting. This causes the wheel to yield somewhat as it contacts with the reel, thereby reducing wear while yet accomplishing effective severance of the thread on the reel. The slight clearance between the feet of the blades allows freedom of motion for the angular movement of the blades as described. Adjustment of the decree of flexibility with which the blades 75 are displaced upon contact with the reel may be

had by varying the size of the cavity provided between the retaining cups 54 and 55 for a given amount of rubber or by varying the amount of rubber which is disposed in a cavity of given size, thus altering the pressure under which the rubber is retained and, consequently, the rigidity of the material. By proper proportioning of the amount of rubber with respect to the size of the cavity, any desired degree of flexibility may be obtained.

The manner in which the outer ends of the blades are disposed is also important. The outer ends are bent at right angles so as to form heads 57 which present cutting edges for the severance of the thread. A narrow slot is necessarily provided through which the blades 63 extend, this slot being located between the inwardly curved peripheries of the two shrouds. However, if no precautions were taken to prevent it, thread ends produced by the action of the wheel would pass through this slot and gradually build up around the rotating parts inside the mechanism so as to eventually clog the wheel. For this reason, the heads 57, extending parallel to the axis of the spindle 42, should overlie the inwardly curved edges of both shrouds in order to prevent thread ends from working into the center of the wheel. The wheel otherwise presents no parts which would tend to build up a mass of thread ends since the face of the rotating shroud 45 is practically flat and provides no exposed rotating surface on which a thread end can wind and cause trouble. The stationary shroud 47 presents no problem in this regard since it does not rotate and merely directs random ends of thread away from the blade slot between the two shrouds.

As the rotatable shroud 45 and the blades 63 rotate at a high rate of speed in the same direction as the reel, causing the blades to move in the opposite direction to the surface of the reel at the point of contact, considerable windage is set up which acts to blow the free thread end, which has just been formed by the action of the blades against the surface of the reel, away from the surface of such reel. Such windage may be found sufficient to effect removal of the thread or it may be desired to increase this windage by providing air passages 58 through which air will be sucked by the impeller action of the blades and will pass between the two shrouds to be blown out through the blade slot at the periphery of the wheel. This provision increases the available windage and removes the thread more vigorously, if such is desired.

Since the thread-removing mechanism must operate in the presence of the liquid which is being showered upon the reel, it is necessary to construct the device so that the corrosive action of any chemicals in the liquid will not cause a breakdown. This may be done in the case of the radial blades by making them of stainless steel when intended to be used in the presence of caustic reagents and of aluminum alloy for acid and all other baths. Other resistant material may, of course, be substituted. The same materials may be used for other exposed metallic surfaces, such as the rotating shroud, the retaining cups and the nut, all of which may be made of stainless steel or aluminum alloy or other resistant material. Stationary shroud 47 may be made of bakelite or similar resin compound which is resistant to corrosion but need not have the strength necessary in the material of the rotating parts. The assembly as a whole is screwed into the protective housing and bracket 18, as de- 75

scribed, so that any members within the housing will be protected from the reagents and will not require resistant material. Thus, the spindle 42 may be made of common steel and the drive 5 pulley 43 of fiber. Likewise, the belt 22 may be made of rubber composition or other material suitable for its function without regard to its chemical-resisting properties, since the belt is also fully protected in the bracket.

10 The action of this particular transfer wheel is as hereinafter described.

The jack shaft 24 drives pulleys 23 over which runs a belt 22 which, in turn, drives the spindle 42 of the transfer wheel. This causes the rotatable shroud 45 and the radial blades 63 to rotate in opposition to the reel with which the mechanism contacts. As the heads 57 of the blades strike the surface of the reel, they sever the thread which has reached or nearly reached 15 the end of the reel and the thread end snaps away from the reel and into the air stream from the wheel. As the blades contact with the reel, they are pushed back slightly by the friction and are thus angularly displaced so as to bring a given head 57 nearer to the axis of the wheel as it slides by the reel and thus reduce wear on the contacting surfaces. This action is possible due to the resilient mounting 53 for the blades. At 20 the same time, air will be drawn in through the passages 58 and blown out between the shrouds 45 and 47 so as to increase the windage available for removing the thread.

After the thread has been caused to wind over all of the reels necessary in order that it may 35 be properly treated and is being collected on a packaging device or otherwise, the series of transfer mechanisms which have transferred the thread in turn from reel to reel are preferably stopped from rotating until another transfer 40 is necessary. It might be expected that the wheels, permanently positioned adjacent the reels so as to sever the thread on such reels, would cause wear of the reel surface and blade heads since the spinning reel continues to 45 rotate. Such wear is, however, negligible due to the fact that the negative clearance between reel and transfer device is very small, being only great enough to permit the blades 63 to sever a thread on the reel and even this slight contact is still further minimized due to the fact 50 that the transfer wheels tend to come to rest in such a position that the lowermost point of the adjacent spinning reel lies in the space between two blades rather than against any one 55 blade.

Viewing the invention as a whole, a machine wherein each thread end passes over a plurality of reels is put in operation by starting the various reels rotating and applying threads from 60 the spin bath to each of the initial reels. The thread travels across each initial reel until it reaches the end of the reel, where any one of the transfer mechanisms mentioned, including that particularly described above, may be located. As 65 the thread reaches the region in which the transfer mechanism contacts with the reel, the severing elements of the wheel sever the thread without any attention on the part of the operator and the windage of the wheel blows this thread away 70 from the reel, it being understood that the wheel moves in the opposite direction to the reel at the point of contact. The wheel is preferably mounted on the line of centers between two reels since this provides the shortest path of travel from one 75 reel to another. However, the thread-removing

device may be located so as to contact with any portion of the lower half of the surface of the reel and still effect a transfer. The windage of the wheel should be sufficient both in quantity and velocity to blow this free end away from 5 the moist surface of the reel.

After this free thread end becomes long enough, it billows out and forms a loop which contacts with the surface of the next lower reel and is quickly drawn taut. The transfer of the 10 thread is now complete. This action will take place automatically for each succeeding reel until the thread is run off to the place of collection. When this has been accomplished, the machine has been placed in operation as far as 15 the given thread end is concerned. At the same time, parallel reels will also be placed in operation and a multiplicity of threads will commence to run off the last or dry reel and be collected. One thread or many threads can then be set up 20 on the reels, a single thread which has become broken being set up by turning on all of the transfer wheels as a unit, since the previously running threads do not reach their respective transfer wheels and are not severed thereby. 25 The transfer mechanisms can be shut down when all of the threads are set up, by turning off the motor which drives them, but even the simple operations of turning a motor on and off can be dispensed with and the reels left rotating if 30 desired.

It is intended that the patent shall cover, by suitable expression in the appended claims, whatever features of patentable novelty reside 35 in the invention.

What is claimed is:

1. A continuous thread-processing machine comprising a plurality of serially disposed thread-advancing thread store devices upon each of which the thread is subjected to treatment and, 40 associated with said thread store devices, independent thread transfer means operating, in the event of an interruption in the continuity of the thread, to initiate automatic transfer of the new leading end from one thread store device to another thread store device. 45

2. A continuous thread-processing machine comprising a plurality of serially disposed thread-advancing thread store devices upon each of which the thread is subjected to treatment and, 50 associated with said thread store devices, positively operating thread transfer means adapted, in the event of an interruption in the continuity of the thread, to initiate automatic transfer of the new leading end from one thread store device 55 to another thread store device.

3. A continuous thread-processing machine comprising a plurality of serially disposed thread-advancing thread store devices upon each of which the thread is subjected to treatment and, 60 associated with said thread store devices, rotary thread transfer means adapted, in the event of an interruption in the continuity of the thread, to initiate automatic transfer of the new leading end from the surface of one thread store device 65 to the surface of another thread store device.

4. A continuous thread-processing machine comprising a plurality of spaced thread store devices arranged in such manner with respect to each other that adjacent thread store devices are 70 in generally superposed relation and, associated with said thread store devices, independent thread transfer means operating, in the event of an interruption in the continuity of the thread, to pass a new leading end automatically from an upper 75

thread store device to a lower thread store device.

5. A continuous thread-processing machine comprising a plurality of spaced thread store devices arranged in such manner with respect to each other that adjacent thread store devices are in generally superposed relation and, associated with said thread store devices, positively operating thread transfer means adapted, in the event of an interruption in the continuity of the thread, 10 to pass a new leading end automatically from an upper thread store device to a lower thread store device.

6. A continuous thread-processing machine comprising a plurality of spaced thread store devices arranged in such manner with respect to each other that adjacent thread store devices are in generally superposed relation and, associated with said thread store devices, rotary thread transfer means adapted, in the event of an interruption in the continuity of the thread, to pass a new leading end from the surface of an upper thread store device to the surface of a lower thread store device.

7. A continuous thread-processing machine comprising a plurality of generally cylindrical thread-advancing thread store devices disposed in spaced, vertically stacked relation, and, associated with said thread store devices, independent

thread transfer means operating, in the event of an interruption in the continuity of the thread, to initiate automatic transfer of the new leading end from an upper thread store device to the next lower thread store device. 5

8. A continuous thread-processing machine comprising a plurality of generally cylindrical thread-advancing thread store devices disposed in spaced, vertically stacked relation and, associated with said thread store devices, positively operating thread transfer means adapted, in the event of an interruption in the continuity of the thread, to initiate automatic transfer of the new leading end from an upper thread store device to the next lower thread store device. 10 15

9. A continuous thread-processing machine comprising a plurality of generally cylindrical thread-advancing thread store devices disposed in spaced, vertically stacked relation and, associated with said thread store devices, rotary thread transfer means adapted, in the event of an interruption in the continuity of the thread, to initiate automatic transfer of the new leading end from the surface of an upper thread store device to the surface of the next lower thread 20 25 store device.
